UNITED STATES PATENT OFFICE.

LEO SOLHEID, OF DUSSELDORF, GERMANY.

FLUSHING APPARATUS.

1,423,634.

Specification of Letters Patent. Patented July 25, 1922.

Application filed February 3, 1922. Serial No. 533,883.

To all whom it may concern:

Be it known that I, LEO SOLHEID, a citizen of the German Republic, and residing at Dusseldorf, in the German Republic, 5 have invented certain new and useful Improvements in Flushing Apparatus, of which the following is a specification.

The present invention has reference to improvements in flushing apparatus such as 10 used for instance in connection with water closets and urinals, and it relates more particularly to that class of flushing apparatus in which, by the lifting of a siphon bell, variable quantities of flushing water may be 15 discharged from the supply tank, for enabling the user to obtain full or partial flushings at will.

For the purpose of explaining the invention a constructional embodiment thereof 20 has been shown in the accompanying drawing, in which the same reference characters have been used in all the views to indicate corresponding parts. In said drawing.—

Fig. 1, is a longitudinal section of the 25 apparatus.

Fig. 2, is a plan of the same.

Fig. 3, is a cross-section of the same, and

Figs. 4 and 5, are a vertical section and a 30 plan view showing the aerating valve of the siphon bell on an enlarged scale.

Fig. 6 is a fragmentary vertical section through the siphon means in the position of rest, and Fig. 7 shows a similar section with the bell in raised position discharging 35 water through the lower ports.

In the drawings the new flushing apparatus is shown by way of example in connection with a water-closet, which latter comprises the several elements well known 40 in the art. The flushing pipe *a* leads from the supply tank *x* to the closet bowl. From the siphon bell *u* depends the standpipe *n*, rigid and concentric therewith, with its packing washer *t*, which pipe is provided 45 near the upper extremity with passages *q* and below with passages *z*. The bell is operated by a rock-lever *e*, fulcrumed to the tank at *i*, to the other end of which lever is linked the pull rod *s* with handle *g*. The 50 supply of water to the tank is controlled by the valve *k* operated by the float *l*.

The operation of these parts is succinctly the following: If the bell *u* is lifted (Fig. 7) by a straight pull on the rod *s*, 55 water will flow from the tank through the passages *z* into the flushing pipe *a*. The

flowing water entrains air out of the pipe *n* and thereby immediately causes air rarefaction in this pipe. If now, after a short lift, the bell is let down again by letting go of the pull rod, this rarefaction will suck up water standing under the bell, so that it will flow through the ports *q* into the central standpipe *n*; and this will continue as long as there is water in the tank, since the 60 column of water discharging through the flushing pipe *a* continuously siphons water out of the tank.

To the top of the bell *u* an air-vent pipe *r* is secured which is provided with one or 70 more air inlets *o* adapted to be closed by a rotary valve *c* in the form of a cylindrical cap having ports *o*¹ corresponding to the inlets *o*. The valve *c* is adapted to be operated by means of an arm *h* made integral 75 therewith. The said arm is connected by a link *f* with a horizontal arm *b* forming the upper end of the drawbar *s* and acting as a lever. The drawbar is mounted along the wall, so as to be capable of longitudinal 80 and rotary motion. The rotary motion of the valve *c* is limited in one direction by a cranked portion *v* of the link *f* and in the other direction by the contact of the arm *b* of the drawbar *s* with an abutment piece *w* 85 of the flushing tank *x*. The lower end of the drawbar has a horizontal arm *g* which may be provided with instructions for the use of the apparatus.

If the rotary valve *c*, the lever mechanism *f*, *b* and the handle *g* occupy the position shown in Fig. 2 by full lines, the air inlet of the tube *r* is open, because the lateral perforations of the tube *r* and cap *c* correspond.

If it is desired to produce one or several weak flushing actions, it is sufficient to turn the lever *h* from the position shown in Fig. 2 by broken lines into the position shown by full lines, thereby opening the 100 air inlets of the aerating tube, then to pull the drawbar *s* downward and, when the desired quantity of water has been discharged from the flushing tank, to release the handle and drawbar. This operation 105 may be repeated several times, as long as the tank contains flushing water.

If it is desired to produce a strong flushing effect and to discharge the whole contents of the flushing tank, the drawbar *s*, 110 after the lever *h* has been turned into the position shown in Fig. 2 by broken lines

and thereby the air inlet closed, is drawn downward and then released again (as is done in ordinary flushing apparatus).

With this invention it is possible, in case 5 a full flushing action has been started by mistake, to interrupt the same, for which purpose the handle *g* is turned and thereby the air inlet opened.

On the other hand it is possible, to convert 10 an accidentally started partial flushing action into a full flushing action by closing the air inlet, while the partial flushing is in progress.

While in describing the invention reference 15 has been made to a particular example embodying the same I wish it to be understood that my invention is not limited to the construction shown in the drawing, and that various changes may be made in the general 20 arrangement of the apparatus and the construction of its parts without departing from the invention.

I claim:

1. In a flushing apparatus of the character 25 set forth, in combination with a siphon bell including a central standpipe presenting top and bottom ports, and means for operating said siphon bell, an aerating device for at will preventing air rarefaction within 30 said siphon bell, and said aerating device adapted to be operated by a movement of said siphon bell operating means different from that for operating said siphon bell.

2. In a flushing apparatus of the character 35 set forth, in combination with a tank, a float-controlled water valve, and a siphon bell, including a ported standpipe controlling the tank discharge, aerating means located wholly above the normal water level in said 40 tank and communicating with the interior of said siphon bell, means including a pull rod for operating said siphon bell by a longitudinal pull and for operating said aerating means by a rotary movement of said pull 45 rod.

3. In a flushing apparatus of the character

set forth, in combination with a siphon bell including a rigidly centrally depending ported standpipe, pull rod means for operating said siphon bell for full flushings, and 50 means for operating said siphon bell for partial flushings, comprising a ported casing on said siphon bell above the normal water level and communicating with the interior of said bell, a ported cap over said ported casing, and means operated by said pull rod means for relatively displacing said cap and said casing for placing the respective ports thereof into or out of register.

4. In a flushing apparatus of the character 60 set forth, the combination with a tank including a float-controlled water inlet, of a siphon bell, including a ported standpipe, controlling the water outlet, siphon breaking means comprising a casing having ports 65 and communicating with the interior of said siphon bell, a cap snugly holding said casing and presenting ports adapted to be placed into or out of register with said casing ports, and said ports lying above the highest water 70 level in said tank, and means for operating said siphon bell for full flushings by a straight downwardly directed movement and for operating it for partial flushings by a combined downward and rotary movement 75 of one of the elements of said operating means, the latter comprising a pull rod, a cranked handle at the lower end thereof and a lever arm at its upper end, a rock-lever pivoted to said tank and linking said pull 80 rod to said siphon bell, a lever arm extending laterally from said siphon breaker cap, a link connecting said cap lever arm to said pull rod lever arm, and means limiting the operative displacement of said siphon 85 breaker operating means.

In testimony whereof I affix my signature.

LEO SOLHÉID.
